UNITED STATES PATENT OFFICE.

NESTOR ROLLAND AND CAMILLE ROLLAND, OF BRUSSELS, BELGIUM.

MERRY-GO-ROUND.

SPECIFICATION forming part of Letters Patent No. 558,114, dated April 14, 1896.

Application filed January 27, 1894. Serial No. 498,237. (No model.)

To all whom it may concern:

Be it known that we, NESTOR ROLLAND and CAMILLE ROLLAND, residing at St. Gilles, Brussels, in the Kingdom of Belgium, have invented certain new and useful Improvements in Merry-Go-Rounds, of which the following is a specification.

Our invention relates to an improved merry-go-round wherein figures of horses are caused to move around a central axis and receive not only a circular, but an oscillating motion to resemble the movement of a horse, and may also receive vertical undulatory motions during the revolution of the horses to give a more perfect horse motion, as in galloping, and also to cause the horses to leap over obstructions placed in their path, such as bars, bushes, or hurdles, and thus afford amusement when used as a toy or exercise and pleasant recreation when made upon a sufficiently large scale to admit of supporting either children or grown persons upon the horses.

Our invention consists in certain constructions and combinations of parts hereinafter particularly described and claimed, with reference to the accompanying drawing, which represents a side elevation of a merry-go-round embodying our invention, showing the platform in section, the driving-shaft and supporting-gudgeon broken away, and the supplemental guide-plates shown by dotted lines.

The gudgeon A, supported by a frame in the usual manner, (not shown in the drawing,) forms the central axis of the large balance-wheel B, which is connected by suspension-bars C with the revolving frame D, which supports the horse-figure frames E and carries the said frames and horses F around with the balance-wheel in a circular path.

The frame D is supported by depending pedestals D' and flanged rollers D'', journaled at the lower end thereof, which rest upon a circular track D'', the flanges d upon the said rollers bearing against the side of the said rail and serving to hold the frame D steady in its revolutions.

The horses F are modeled to represent a horse in the position of galloping, and the galloping motion is given to the figures by means of parallel vertically-moving bars E' E'' E''', coupled together by rocking links E⁴, to the

ends of which brackets G are pivoted at g, which support upon their upturned ends g', by means of pivotal or hinged connections g², 55 the forward and rear end of the horse.

The pivotal connections e' e'' e''' of the vertically-moving frame-bars E' E'' E''' and rocking parallel-motion links E⁴, as well as the pivot g of the brackets G, are all preferably 60 turned, pivot or stud bolts fitting in bored boxes which admit of a free articulation, and the upper ends of the said frame-bars E' E'' E''' are supported in straps or mortises in the frame D, which will admit of a free vertical 65 movement.

The middle vertical frame-bar E' is longer than the outer bars E'' E''' and has an upper end support in a bracket H. (Shown by dotted lines in the drawing.) The lower end 70 of the bars E'' E''' have bearings i, which support the spindles of rollers I, and the latter rest upon an undulatory or waved track K, securely bolted to the base or ground concentric with and beneath the circular revolving 75 frame D, which carries the said vertical frame-bars, and by which means the said vertical bars are given a reciprocating motion and the rocking parallel-motion links E⁴ and horses F are given both a vertical and a rocking motion, causing the latter to receive a motion closely resembling that of a galloping horse. Some of the undulations K' are made 80 higher than the undulations K'', which will cause the horses to jump higher and farther 85 at such intervals, and obstructions L, simulating a hedge, hurdle, or cross-bar placed across the path of the horse at said intervals, may thus be cleared by the horses in their leaping motion in a natural and fascinating 90 manner.

A platform M is placed around the undulatory track beneath the path of the horses and will provide an outer guard and convenient means for mounting the horses.

The revolving frame D is connected by gearing N, the shafting of which is broken away, and is driven in any well-known or preferred manner.

What we claim as our invention, and desire to secure by Letters Patent, is—

1. A merry-go-round comprising a revolving frame carrying a vertically-reciprocating supporting-bar, and two parallel independ-

ent vertically-moving bars pivoted upon the supporting-bar by rocking parallel-motion links, and supported upon an undulatory track and horses carried by said bars and 5 caused to receive a lifting as well as rocking motion, substantially as described.

2. In a merry-go-round, the combination with the supporting-wheel of the vertically-moving supporting-bar E', bracket H, vertically-moving bars E², E³, carrying rollers I, parallel-motion rocking links E⁴ pivoted at their middle portions to the bar E' and at their 10 ends to the bars E², E³, an undulatory track

supporting the said bars and links, and brackets G pivotally supported upon said 15 links and carrying horses F pivoted thereon, substantially as described for the purpose specified.

In testimony that we claim the foregoing as our invention we have signed our names in 20 presence of two subscribing witnesses.

NESTOR ROLLAND.
CAMILLE ROLLAND.
